TYPEWRITING MACHINE

Henry L. Pitman, Hartford, Conn., assignor to
 Underwood Elliott Fisher Company, New
 York, N. Y., a corporation of Delaware

Application January 28, 1936, Serial No. 61,135

52 Claims. (Cl. 197—66)

This invention relates to typewriters and more particularly to typewriters in which a platen is rotated a predetermined number of line-spaces at one time.

5 A feature of the invention is the provision of means that rotates the platen to present the first line of a succeeding form irrespective of the number of lines imprinted on the preceding form, on a continuous work-sheet.

10 A feature of the invention is the provision of means for the automatic feeding of a work-sheet as above set forth by an automatic carriage-return mechanism.

15 Another feature of the invention is the provision of means for the rotation of the platen to feed a work-sheet by means of a screw mounted on the platen-shaft, and a toothed wheel inter-engaging with the screw and held stationary during the carriage return, whereby the work-sheet is fed forwardly each time to the predetermined initial line.

20 Another feature of the invention is the provision of means for lifting and for holding the platen-detenting roll out of engagement during the automatic rotation of the platen and its automatic engagement with its notched wheel at the initial line of each successive work-sheet, and preventing normal line-spacing during the automatic feed.

25 Another feature of the invention is the provision of means that inaugurates the carriage return and the automatic work-sheet feed by the single operation of tripping a key on the front of the typewriter.

30 Another feature of the invention is the provision of a toothed wheel fast on the platen and a stop co-operative therewith to prevent overthrow of the feed mechanism, and of the work-sheet, during the automatic rotation of the platen.

35 Another feature of the invention is the provision of means that automatically stops the carriage-return mechanism concomitantly with means that automatically stops the automatic rotation of the platen.

40 Another feature of the invention is the provision of mechanism to throw out the platen-detent roll and to lock the line-space mechanism by power, which is done by automatically connecting said mechanism to the power-driven carriage-return rack.

45 Another feature of the invention is the provision of means that presents the first line of a succeeding form irrespective of the number of lines imprinted on the preceding form, said

means permitting setting for forms of different size.

5 Another feature of the invention is the provision of means for automatically rotating the platen a predetermined total number of line-spaces less the number of line-spaces the platen has been already rotated by said line-spacing mechanism.

10 Another feature of the invention is the provision of a shaft mounted on the platen-shaft for rotation therewith and having a helical screw and means mounted on the frame which by the motion of the carriage-return acts on said screw to line-space the platen.

15 Another feature of the invention is the provision of a covering for the helical screw and the coacting mechanism which keeps out dust and dirt and protects the parts from accidental injury or displacement, as well as protects the operator.

20 Other features of the invention are the provision of various improved mechanical constructions, positive in action and durable in construction, contributing in whole or in part to the performance of the novel functions above set forth.

25 Other features and advantages will hereinafter appear.

In the accompanying drawings:

30 Figure 1 is a perspective view with some of the parts sectioned, showing the imprinting of the first or head line on a telephone-toll bill form.

35 Figure 2 is a section through the right end of the platen, showing the aperture for assembling the screw-shaft at the left end of which shaft a pick-up arm is shown, but omitting the central solid platen-shaft.

40 Figure 3 shows a part of the automatic platen-rotating assembly, at the left the overfeed stop for engagement with the ratchet on the right end of the platen as shown in Figure 1 and the spring mounting for the movable stop-tooth which interengages with a tooth on the screw-wheel.

45 Figure 4 is a right-end elevation, partly in section, showing the automatic carriage-return link locked behind its keeper and the "new bill" key in the normal, inoperative position.

50 Figure 5 is a perspective view of the screw-wheel assembly with the parts separated.

Figure 6 is a plan view with the left end of the platen in section and other parts broken away, and with the mechanism in position for typing a line of a bill.

55 Figure 7 is a perspective view showing a

modification to permit normal line-spacing to an aggregate extent of more than one platen rotation before the automatic rotation of the platen is inaugurated.

Figure 8 is a perspective showing the extreme returned position before the carriage has dropped to the left one space to the first writing position, with the hollow screw-shaft arm abutting the inside platen-pin, and the latched carriage-return rack locking the line-space lever and holding the line-space detent released, although the "new bill" lever has been restored to normal position.

Figure 9 is a vertical section through the platen near its left end and showing the carriage returning and the line-space detent-roll thrown out.

Figure 10 is a front elevation, a central portion being broken out, showing the beveled edges of the stop on the back of the carriage-return rack and of the lever-plate interengaging in the latched position, after the detent-arm has been disengaged, but before the line-space pawl has engaged its platen line-space ratchet-wheel.

Figure 11 is a perspective, with parts in section and parts broken away, the carriage being advanced to the extreme left and the automatic carriage-return trip being released and about to close the clutch, and the inside platen-pin turned about half a platen rotation away from the screw-shaft arm.

Figure 12 is a perspective of the screw-wheel mounted on the helically grooved shaft and the positions of the coacting parts after the carriage has returned one letter-space and before the work-sheet is automatically fed, the detent-tooth being in line with the screw-wheel, but the fixed bracket-tooth at the right of the screw-wheel still out of engagement therewith.

Figure 13 is an end view of the parts shown in Figure 9, but with the parts in the normal position, and the detent-roll in engagement with the platen ratchet-wheel.

Figure 14 is a side elevation, partly in section, viewed from the right, showing the carriage released and advancing or jumping to the extreme left as the "new bill" key is depressed.

Figure 15 is a perspective view showing a telephone toll bill in the first printing position, and the automatic platen-rotating mechanism.

Figure 16 is a right side elevation showing the automatic carriage-return mechanism in the normal or inoperative position.

A work-sheet 20 as shown is continuous with repeating identical forms demarcated by lines of weakness to facilitate their separation by tearing after the typing thereon has been completed. The forms as illustrated are prepared for telephone toll bills or invoices. There is variation in the number of items or toll charges imprinted on each form, so that the number of lines to be typed on each form is a variable, but the next form must always start on the first line. The invention is shown embodied in an Underwood standard type-writer having a frame 21, a front-plate cross-piece 22, having a front carriage-rail 23, a front carriage-roller 24, and a carriage-frame 26, having a front piece 25. No case shift need be provided for typing telephone toll bills. Type-keys 27 operate the usual type-bar 28. A platen 29 has an inner cylindrical chamber for purposes which will appear hereinafter and feed-rolls 30 engage the platen for feeding the work-sheet.

An automatic electrically-operated carriage-return is shown herein, which may be operated

by a trip-finger 31 adjacent the keyboard on the front of the machine, which actuates a cam 32 which is mounted on the forward end of a link 33, normally locked in the forward position by a keeper or latch 34, which lies in a notch 35 cut out in the under surface of the link 33. A spring 36 tied to the frame tends to draw the link rearward to actuate a switch and a clutch on the rear of the type writer-frame.

An automatic starting of the carriage-return is effected by the following construction. A horizontal pin 37 in the side of the link 33 is positioned to engage a rock-lever 38 mounted on a stud 39, which in turn is positioned in the side of the frame 21. A pivot-pin 40 connects the forward end of the rock-lever 38 with the upper vertical link 41, which is pivoted at its upper end to an ear 42, extending forwardly from a plate 43 screwed fast on a tooth-bar 44 which is mounted on arms 45 loose on a rock-shaft 46, which has a longitudinal groove and is mounted in the sides of the frame. A line-end margin-stop 47 is slidable on the shaft 46 and adjustably lockable by the teeth of the bar 44. At the left end of the stop 47 is a stop-post 48, and a cam-pawl 49 is pinned on the side of the post 48 and overlies the bar 44. These parts are shown in Figures 1 and 4 in their normal or inoperative position, and in Figure 11 depressed and tripping the automatic carriage return. A forwardly-extending lug 50 on the front piece 25 of the carriage-frame depresses the cam 49, as it overrides it to engage the stop-post 48, to depress the bar 44 and trip the link 33 to actuate the carriage-return switch and clutch.

An arm 51 is mounted on a rock-shaft 52 and is pivotally connected with the link 33. An arm 64 is also mounted on the rock-shaft 52 and is connected by a link 53 with an arm 54, which is tied to and rocks a shaft 55 on which is secured a cam-arm 56, which continuously lies in an annular groove 57 which is integrated with a gear-pinion 58, also in turn integrated with a jaw 59 of a clutch with which it is rotatable as a unit on a shaft 60 on which is fixed a complementary clutch-jaw 61. Fast on the rear end of the shaft 60 is a wheel 62 driven by worm-gear 63 enclosed in a housing 65 and operated by an electrical motor which therefore returns the carriage through the engagement of the driven pinion 58 with a rack 66. A link 192 may be pivotally connected with the shaft 52 to actuate a motor starting and stopping switch 193 represented merely diagrammatically in Figures 4 and 16.

A line-start margin-stop 67, Figure 8, provided with a toothed detent-arm 68 engaging a vertically notched rod 69, has an arm 70 slidable on and splined to the grooved rock-shaft 46 to rock the latter and the arm 70 carries a vertical cam-plate 71 which normally lies in the path of the carriage-lug 50. A stop-lug 72 extending rearwardly from the margin-stop 67 engages a counter-stop 73 mounted on the front piece 25 of the carriage-frame. Referring to Figure 16, an arm 74 fast on the rock-shaft 46 is pivotally connected with a link 75 which in turn is pivoted to a slide-arm 76 provided with a slot 77 fitting a guide-pin 78, mounted on the frame of the typewriter, said slide-arm being connected to the rock-shaft 55, Figure 11, for automatically disengaging the clutch 59, 61, and stopping the motor when the carriage-lug 50 engages the arm 70 and thereby rocks the shaft 46 to end the carriage-return run.

The automatic feed of the continuous work-sheet 20 by means of the automatic carriage-return mechanism, which has been described above, 75

in one embodiment of the invention is procured by the following mechanism. A "new bill" key 79 mounted on the front of the typewriter is adapted to be depressed only while the carriage is feeding 5 to the left and actuates a lever 80, which is pivotally connected with an arm 81 which has a vertical extension 82, the edge of which lies in the path of a cam 83 mounted on the under side of the front rail 25 of the carriage. A shoulder 84 on the arm 81, in the depressed position of the arm 81, engages under a bracket 85, which is mounted by means of ears 86 on the frame 21. A spring 87 holds the shoulder 84 latched in the bracket 85. The lever 80 is pivoted at the rear on 10 a rod 88 mounted in the frame of the machine, and a coil-spring 89 also mounted on the frame tends to hold the lever 80 in the upright position. The arm 81 holds the "new bill" key 79 down in its operative position until the cam 83 moves, by 15 the return of the carriage into engagement with the vertical extension 82 to release it. The cam 83 is so positioned on the front of the carriage that it engages the post 82 after the beveled edge 20 of a stop 188 (Figures 8 and 11) is interengaged 25 with a beveled edge 191 of a lever-plate 107, as will be hereinafter described.

Link 90 intermediately pivoted on the key-lever 80 is also pivotally connected with an arm 91 fast on a rock-shaft 92 mounted in the frame 30 of the typewriter. Hook-arm 93, Figure 4, fast on the rock-shaft 92, engages a pin 94 mounted at the rear end on the side of a rock-arm 95 pivoted on a pin 96 fast on the frame, said arm 95 carrying a roll-wheel 97 which underlies and 35 engages an escapement-rack 98, so that when the "new bill" key 79 is depressed, the roll-wheel 97 lifts the rack 98 up off an escapement-pinion 99, which has an escapement-wheel 100. Arms 101 mounted on pivot-studs 102 at the ends of 40 the carriage beneath the platen 29 support the escapement-rack 98. A spring-drum 103 for feeding the carriage actuates a tape 104, which is secured to the carriage. The disengagement of 45 the escapement-rack 98 from the escapement-pinion 99 permits the carriage to travel to the end of a line under the power of the spring-drum 103, and also permits the carriage-lug 50 to engage the cam 49 of the stop 47, thereby inaugurating the electrical automatic return of the 50 carriage, as clearly shown in Figures 4 and 14.

The mechanism for lifting and for holding the platen-deton-roll out of engagement with the platen, and also for locking the line-spacing mechanism during the automatic platen feed of the work-sheet 20, is now described. A lever-plate 105 is secured by screws 106 to the rock-shaft 92, and is provided at its top with a forwardly turned edge for engaging a lower extension 108 of the lever-plate 107, and the latter is secured on a rock-shaft 109 mounted in the carriage-frame. Screw-collars 110 (Figure 1) hold the shaft 109 adjustable, sidewise on the carriage, in the ends of the frame 26. At the right end of the carriage, on the rock-shaft 109, 5 is secured an arm 111 which engages the under side of the rear end of a lever plate 186, which will be hereinafter described.

A finger-arm 112 (Figure 1) is mounted on the left end of the shaft 109 rockably therewith, and has fingers 113 which grip the upper flat extension of a bracket 132 hereinafter described, and proximate to the left end of a back cross-piece 114 of the carriage. A detent-arm 115 (Figures 9 and 13) pivoted on the left end of the carriage carries a detent-roll 116 and a side arm

117, mounted on a pivot-pin 118, is limited in movement by a stop-pin 119, while a coil-spring 120 holds the arm 117 in its predetermined relationship to the detent-arm 115.

An end-bracket 121 (Figures 6, 9 and 13) formed on an extension 135, Figure 6, from the rear of the carriage and coacting elements provide for the usual automatic line-spacing. An idler-pinion 122 engages a side rack 123 mounted on the left end of the carriage-return rack 66. 10 A lower lateral extension 124 from the bracket 121 carries the idler-pinion 122, and is apertured to form a bearing for a segmental gear 125, which meshes with said pinion 122 and is mounted on the lower end of a central post 126, which carries fast on its upper end a lug-collar 127, which engages and actuates a stop-arm 128 mounted on a line-spacing slide 137. A collar 129 on the post 126 supports a pin 130 working as a spline in a vertical slot 131 in the bracket 132, which is also mounted on the post 126, and has at the lower end a cam-arm 195, which in the upper position of the bracket 132 engages the side arm 117 on the detent-arm 115. A screw 133 adjustably secures the collar 129 on the post 126. A coil-spring 134 surrounds the post 126 and tends to hold the bracket 132 in the lower position. 15 20 25

A ratchet-wheel 136 (Figures 6, 9 and 13) for line-spacing the platen is mounted on a platen-shaft 145. The line-space slide 137 has pivoted thereon in a position suitable for engagement with the ratchet-wheel 136, a lever 138 carrying a pawl 139, and is slidably mounted on superstructure 140 (Figure 1) on the side of the carriage. Line-spacing for one, two or three line-spaces is controlled by the setting of a control-lug 199 and its handle 200, and an overthrow stop 198 limits the extent of line-spacing movement of the lever 138. As shown in Figure 10, tongues 197 at either end of a rack-supporting bracket 142, as shown in Figure 4, and companion slots 196 in the rack-bar 66, slidably support the latter, thereby permitting the rack to move endwise relatively to the carriage to operate the line-spacing mechanism before returning the carriage. A hand roller 141 is mounted on each end of the platen-shaft 145. The bracket 142, which supports the rack-bar 66, is fastened by screws 143 on the under side of the back cross-piece 114 of the carriage in a position in front 50 of a rear carriage-rail 144.

The platen-shaft 145 (Figure 6) has at the left end a ball-bearing race 146 to take up the friction of the end thrust of the platen 29 during the automatic rotation of the platen to feed a 55 work-sheet. A left end-plate 147 on the platen 29 carries an inwardly-extending pin 148, which is parallel to the shaft 145 and to a hollow shaft 149, which fits rotatably on the platen-rod 145, and carries a stop-arm 150 radially mounted 60 and engaging the pin 148. The hollow shaft 149 is loosely and rotatably mounted on the platen-shaft 145, so that the platen 29 and the pin 148 can turn freely in line-space rotation independently of the hollow surrounding shaft 149 and therefore away from the stop-arm 150. This construction permits the platen to turn freely when line spaced by the usual line-spacing mechanism, but the hollow shaft 149 does not turn. The left end of the 70 platen 29 has a rotatable bearing on the shaft 145, in a side piece 145a mounted on the carriage, and the other end of the platen bears on the hollow shaft 149. The platen has a hard rubber outer surface 151, and a hard inner layer 152, 75

which provides a hollow chamber between the inner wall of the layer 152 and the rotatable shaft 149. The platen is secured on the shaft against turning by a set-screw 153. The platen 5 has a right end-plate 154 affixed thereon, and over this end-plate is mounted for rotation with the platen an eight-toothed wheel 155, which serves to prevent overthrow during the automatic feeding of the platen as hereinafter described.

The hollow shaft 149 has in its outer surface a helical groove or screw 156. A slot 157 in the end-plate 154, which is clearly shown in Figure 2, permits the insertion of the hollow shaft 149 and its radial arm 150 into the hollow chamber in the platen 29.

At the extreme right end of the hollow shaft 149 is secured a wheel 158 (Figure 8), which has eight equidistant and equally spaced notches 20 thereon, and a detent-lever 159 pivotally mounted in the side frame of the carriage lies in spring 25 pressed contact with one of the notches by the tension of spring 160 secured to the opposite end of the lever and to the side of the carriage. The detent 159 holds the hollow shaft 149 with its 30 helical groove 156 against rotation unless the shaft is positively actuated by the carriage return. A wheel 161 is provided with eight equidistant teeth, and is secured to a Babbitt casting 35 162 provided with an internal helical ridge or screw thread 163 of the same form and pitch as the helical groove 156, in which it is continuously riding. In order to assure perfect conformity the Babbitt casting 162 may be cast directly 40 over the shaft 149 and its groove 156. The pitch of the helical groove 156 and of the helical ridge or screw 163 is such that the hollow shaft 149 may be rotated by the movement of the carriage with reference to the toothed wheel 161 when the latter is secured against rotation.

A reciprocating rod 164 (Figure 1) is slidably mounted at the left in a block 165 attached to the top of a type-bar segment 166 and at the right in a plate 167, which is mounted on the frame 21 by spacing screws 168. A bearing-block 169 is secured on the outside of the plate 167. An adjustable stop in the form of a collar 170 limits the movement to the right of the rod 164, and thereby limits the total automatic line-spacing 45 feed of the platen, or, in other words, the total number of lines that are automatically spaced on the work-sheet.

A bracket 171 (Figures 1, 6 and 8) pinned on the rod 164 is provided with a notch 172, in 50 which the teeth of wheel 161 turn between a left yoke-stop 173 and a right yoke-stop 174, each yoke having diametrically opposed friction edges for sidewise engagement with the toothed wheel 161. A tooth-stop 175 is pivoted for movement 55 toward and away from the toothed wheel 161 on a rod 176 which is supported on and under the bracket 171 in the depending ears 177, and a coil-spring 178 has one end tied to the bracket, and the other end to the toothed arm 175 in such 60 a way that it is constantly tending to lift the tooth 175 into such a position that it would be within a circle parallel to the circumference of the toothed wheel 161 and interposed between the right side of said wheel 161 and the right 65 yoke stop 174 as in Figure 4.

A tooth 179 (Figures 1 and 3) is mounted in the bracket 171 in such a position that it intercepts the teeth on wheel 155, and it reciprocates in a slot under the control of a coil-spring 180 70 surrounding its supporting shaft. It is obvious 75

that as the right end of the platen approaches the bracket 171, the tooth 179 engages with one of the teeth of the wheel 155 to positively check further rotation of the platen 29. A flat yoke-spring 181 bears on the babbitt 162 and holds the wheel 161 and the bracket 171 back, when the carriage drops to the first writing point to release the overthrow tooth 179 from the wheel 155.

A screw fastening 182 on the back cross-piece 114 (Figure 11) of the carriage supports the rear 10 end of a table 183, which carries at its edges forwardly-extending ears 184, in which is mounted a rod 185 to which is fastened the lever-plate 186 by means of screws, or any other suitable means, the lower end of said plate being in engagement with a depending and rearwardly extending cam-jaw 187 of tooth-stop 175.

Referring to Figures 8, 9 and 10, the stop 188 mounted on the back of the rack 66 has a vertical beveled wall, which forms a vertical latch 20 engageable with the beveled edge 191, which is provided on the left end of the lower extension 108 of the lever-plate 107, and latches the lever-plate 107 on the rack 66 during the return movement of the carriage and therefore prevents feed 25 by the line-space pawl 139, and holds the detent-roll 116 out of engagement with the platen during the return movement of the carriage.

A tooth 194 formed in the bracket 171 to the right of the notch 172 engages a tooth of the 30 wheel 161 following the operative engagement of the tooth-stop 175 with a tooth on this wheel.

Referring to Figure 7, a modification is shown of the interlocking structure included in pin 148 and arm 150 at the left end of the platen. A 35 supporting block 201 is mounted on the inside of the platen and carries a finger 202, pivotally mounted, for movement of its free end in the general direction of the axis of the platen, of a pin 203, the end of which finger travels in a 40 helical groove 204 of the hollow-shaft 149. Stop-pin 205 in the left end of the groove provides the actuating stop for the finger 202. This modification provides a construction which permits the use of a work-sheet form having more line-spaces than those provided by a single rotation of the platen. A second stop 209 is provided in the right end of the groove 204.

A paper-chute may be provided having walls 189 (Figure 6) which may be held securely by 50 a tie-rod 190. The platen extension plate 167 may be adjusted by substituting for one of the spacing screws 168 a screw provided with an adjusting nut 206. A dust and dirt protective covering and guard 207 may be provided and fastened on a paper-table 208, see Figure 4.

Operation of the automatic line-space feed

Upon pressing down the "new bill" key 79 (Figure 6), wheel 97 lifts the escapement-rack 60 98 up off the escapement-pinion 99, thereby permitting the carriage to feed under the power of the usual spring-drum 103 (Figure 14) up to the last predetermined letter-space at which the carriage-lug 50 (Figure 1) engages the pivoted cam 49 to rock the lever 38, lift the pin 37, and trip the link 33 over the keeper 34 and so close the switch 193 (Figure 4) and the clutch-jaws 59, 61 to inaugurate the automatic carriage-return. The wheel 161 (Figure 5), fast to piece 70 162, with the helical screw 163, is riding in the helical groove 156 at the extreme end position before the carriage starts to return. Upon the first letter-space movement of the carriage to the right in returning, the toothed wheel 161 has 75

5 moved rightward into the plane of the retracted tooth-stop 175, as shown in Figure 12, and also into the plane of the tooth 194 to enable the latter to check the proximate tooth of the eight 10 equidistant and equally spaced teeth on the wheel 161. As the carriage return continues, the wheel 161 and bracket 171 are idly carried along until checked by means of the stop-collar 170, whereupon the hollow shaft 149 rotates, through 15 further return of the carriage, in the line-space feeding direction until the arm 150 (Figure 1), engages the pin 148, or, in the modification shown in Figure 7 finger 202 turns in groove 204 until it engages the stop 205, and simultaneously thereafter the shaft turns with the platen 29 in 20 the line-spacing direction for the total number of predetermined line-spaces, in eighths of a platen rotation, according to the setting of the collar 170 (Figure 6) on the reciprocating rod 164, 25 mounted in the block 165 and the bracket-plate 167. In the extreme returned position as shown in Figure 4, the margin-stop 73 (Figure 8) interlocks with the stop-lug 72 and the carriage-lug 50 overrides and actuates the cam-plate 71 to 30 tip down the arm 70 and so disengage the carriage-return switch and the clutch. At this time also the spring-pressed tooth 179 interengages with the proximate of the eight teeth on the toothed wheel 155, which is fast on the platen, to 35 prevent overthrow of the line-space feed, and the detent-lever 159 is engaging one of the eight notches in the wheel 158. The collar 170 meanwhile has abutted the inner wall of bracket-plate 167, thereby preventing further movement of 40 the rod 164.

In the first printing position on a new form as shown in Figure 15, the carriage has dropped back one letter-space, but the yoke-leaf spring 181, which bears on the left end face of the piece 45 162, has prevented the screw-wheel 161, the yokes 173, 174, and the overthrow tooth 179 from following the carriage, thereby releasing the tooth 179 from the toothed wheel 155, so that the operator can turn the platen by the hand roller 141 at the left, if desired. After the first 50 letter-spacing in the printing position the carriage has moved two letter-spaces, or two-tenths of an inch, to the left, so that the wheel 161 has moved over to the left side of the notch 172 out of contact with the yoke 174 and into contact with the yoke 173 and out of the path of the tooth-stop 175, causing the latter to interpose itself again between the yoke 174 and wheel 161, so that said wheel 161 is now free to turn idly 55 on the shaft 149 during an ordinary carriage return, that is, one not accompanied by form-feeding. Referring to Figure 6, the carriage return for one letter-space has rotated the wheel 161 only, and for the next letter-space the carriage 60 moves with the wheel but without taking along the bracket 171 and then for three letter-spaces with the bracket 171. As shown in Figure 1, the carriage has advanced eight more letter-spaces together with the bracket 171, and the inner 65 end of the bracket 171 now abuts the supporting block 165, and prevents further movement of the rod 164 to the left. Further leftward movement of the carriage then results in bringing the wheel toward the right end of the groove 156. As the 70 platen is normally letter-spaced the pin 148 moves away from the arm 150, so that in causing the rotation of the shaft 149 automatically it does not line-space the platen until it has picked up the space between the pin 148 and the arm 75 150, that is, the number of line-spaces already

used, and continues then to turn the platen the number of line-spaces remaining from the pre-determined whole number, so that the total combined line-spacing is always the same, and the position is always the first line on the next form 5 irrespective of the number of line-spaces already advanced by the usual line-space lever. To decrease the rotation of the platen one-eighth, the collar 170 is moved two letter-spaces or two-tenths of an inch to the left, and to increase 10 the rotation of the platen one-eighth, the collar 170 is moved two letter-spaces or two-tenths of an inch to the right. In the present embodiment of the invention, the pitch of the groove 156 is such that each one-sixteenth of a rotation 15 is equivalent to one letter-space or to one-tenth of an inch of carriage travel.

Operation of the line-space feed mechanism

20 During the printing of a form at the end of each line the automatic carriage return is set in motion by the engagement of the carriage-lug 50 and the cam-plate 71 (Figure 8). The gear-teeth on the side of the rack 66 initially engage 25 the idler-pinion 122 (Figure 9) and through it the segmental gear 125, to rotate the post 126 and the lug-collar 127 into engagement with the arm 128 projecting perpendicularly from the line-space slide 137 to which is pivoted the line-space lever 138 and its pawl 139, so that the initial return movement of the carriage-rack 30 line-spaces the platen for one, two, or three line-spaces according to the setting of the handle 200, simultaneously moving the pin 148 away 35 from the arm 150, or, in the modification shown in Figure 7, moving the finger 202 away from the stop 205. This operation is continued at the end of each line on the form, and the pin 148 continues to move away from the arm 150, or 40 the finger 202 away from the stop 205, as the platen is line-spaced. When, however, the "new bill" key 79 (Figure 1) is depressed the plates 105 and 107 rotate the rock-shaft 109 to lift the finger-arm 112, which has fingers 113 gripping 45 the top plate of the bracket 132 mounted on the post 126. The lower edge of the bracket 132 is in the form of the extending cam-arm 195 (Figure 13). The collar 129 adjustably secured on the post 126 by the set-screw 133 supports the 50 pin 130, slidably in the slot 131 in the bracket 132, which limits the vertical movement of the bracket against the coil-spring 134, from the position shown in Figure 13 to that shown in Figure 9. In the upper position of the bracket 132 55 as the return rack 66 moves, the segment-gear 125 carries the arm 195 into engagement with the arm 117, pivotally secured to the detent-arm 115 which carries the usual detent-roll 116 at the end, and so moves the detent-roll out of 60 engagement with the platen ratchet-wheel 136, but, as shown in Figure 10, the bevel edge of stop 188 interengages the bevel edge 191 of the lever-plate 107, so locking the carriage-return rack after the detent-roll is thrown out, but before 65 the line-spacing pawl has actuated the platen. This position is maintained during the carriage return, thereby providing a latch which holds the detent-roll 116 out of engagement with the ratchet-wheel 136, and which also prevents feed 70 by the line-space pawl 139. After reaching the extreme returned position the carriage-return clutch is automatically opened. During this line-spacing operation the detent 159 lies in a notch 75 in the wheel 158 and prevents the hollow shaft

149 from turning on the platen-shaft 145, the wheel 161 turning idly in the notch 172.

Variations may be resorted to within the scope of the invention, and portions of the improvements may be used without others.

Having thus described my invention, I claim:

1. In a typewriter, in combination, a frame, a carriage mounted for reciprocatory movement thereon, a platen rotatably mounted thereon, line-spacing mechanism for rotating the platen, power-operated carriage-return mechanism, a key, and means automatically operative under control of said key to return said carriage by means of said carriage-return mechanism and concomitantly, by means of said power-return of the carriage, rotate the platen a predetermined total number of line-spaces less the number of line-spaces the platen has been already rotated by said line-spacing mechanism, whereby in a continuous work-sheet the first line of a succeeding form is automatically presented by means of the power-operated carriage-return and irrespective of the number of lines imprinted on the preceding form.
2. In a typewriter, in combination, a frame, a carriage mounted for reciprocatory movement thereon, a platen rotatably mounted thereon, line-spacing mechanism for rotating the platen, power-operated carriage-return mechanism, a carriage-return key associated with said carriage-return mechanism, a special key, means, automatically operative upon the depression of the special key, to return said carriage by means of said carriage-return mechanism, and platen-rotating mechanism rendered effective by said depression of said special key to operate by means of said power-return of the carriage, to rotate the platen a predetermined total number of line-spaces less the number of line-spaces the platen has been already rotated by said line-spacing mechanism, whereby in a continuous work-sheet the first line of a succeeding form is automatically presented by means of the power-operated carriage-return irrespective of the number of lines imprinted on the preceding form, said first key being used for returning said carriage by power without operating said platen-rotating mechanism.
3. In a typewriter, in combination, a frame, a carriage mounted for reciprocatory movement thereon, means for automatically returning the carriage, a platen rotatably mounted thereon, line-spacing mechanism for rotating the platen, and means automatically operative by the automatic carriage-return mechanism to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.
4. In a typewriter, in combination, a frame, a carriage mounted for reciprocatory movement thereon, a platen rotatably mounted thereon, line-spacing mechanism for rotating the platen, and means comprising a screw automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.
5. In a typewriter, in combination, a frame, a

carriage mounted for reciprocatory movement thereon, a platen rotatably mounted thereon, line-spacing mechanism for rotating the platen, and means comprising a screw, one member of which is mounted on the carriage and the other member on the frame, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

6. In a typewriter, in combination, a frame, a carriage mounted for reciprocatory movement thereon, a platen rotatably mounted thereon, line-spacing mechanism for rotating the platen, and means comprising a screw, one member of which is mounted on the carriage and the other member on the frame, the pitch of said screw being such that one member may be turned with reference to the other member, by the relative movement of the carriage and the frame, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

7. In a typewriter, in combination, a frame, a carriage mounted for reciprocatory movement thereon, a platen rotatably mounted thereon, line-spacing mechanism for rotating the platen, and means comprising a screw, one member of which is rotatably mounted on the platen-shaft and engageable with the platen and the other member mounted on the frame, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

8. In a typewriter, in combination, a frame, a carriage mounted for reciprocatory movement thereon, a platen rotatably mounted thereon, line-spacing mechanism for rotating the platen, means comprising a screw, one member of which is mounted on the carriage and the other member on the frame, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form, and a combined guard and cover over said members.

9. In a typewriter, in combination, a frame, a carriage mounted for reciprocatory movement thereon, a platen having an axial shaft and rotatably mounted thereon, line-spacing mechanism for rotating the platen, and means comprising a hollow screw shaft rotatably mounted on the platen-shaft automatically operative to rotate the platen a predetermined total number of line-spaces less the number of line-spaces the platen has been already rotated by said line-spacing mechanism, whereby in a continuous work-sheet

the first line of a succeeding form is automatically presented irrespective of the number of lines already imprinted on the preceding form.

10. In a typewriter, in combination, a frame, a carriage mounted for reciprocatory movement thereon, a platen having an axial shaft and rotatably mounted thereon, line-spacing mechanism for rotating the platen, and means comprising a hollow screw shaft rotatably mounted on the platen shaft, one end of the platen having a bearing thereon, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

11. In a typewriter, in combination, a frame, a carriage mounted for reciprocatory movement thereon, a platen rotatably mounted thereon, line-spacing mechanism for rotating the platen, and means comprising a central platen shaft, a hollow cylindrical shaft rotatably mounted thereon, a part of said hollow shaft being within the platen, a stop on the platen, and a stop on the hollow shaft engaging said platen-stop, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

12. In a typewriter, in combination, a frame, a carriage mounted for reciprocatory movement thereon, a platen rotatably mounted thereon, line-spacing mechanism for rotating the platen, and means comprising a central platen-shaft, a hollow cylindrical shaft rotatably mounted thereon, a part of said hollow shaft being within the platen, a stop on the platen, a stop on the hollow shaft engaging said platen-stop, a helical groove on the outside of said hollow shaft, and a member mounted on the frame, and adapted to travel in said groove and to cause the rotation of said hollow shaft in the line-spacing direction, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

13. In a typewriter, in combination, a frame, a carriage mounted for reciprocatory movement thereon, a platen rotatably mounted thereon, line-spacing mechanism for rotating the platen, and means comprising a central platen-shaft, a hollow cylindrical shaft rotatably mounted thereon, a part of said hollow shaft being within the platen, a stop on the platen, a stop on the hollow shaft engaging said platen-stop, a helical groove on the outside of said hollow shaft, and a toothed wheel mounted on the frame, and adapted to travel in said groove and to cause the rotation of said hollow shaft in the line-spacing direction, automatically operative to rotate the platen a predetermined total number of line-spaces less the number of line-spaces the platen has been already rotated by said line-spacing mechanism, whereby in a continuous work-sheet the first line of a succeeding form is automatically presented

irrespective of the number of lines already imprinted on the preceding form.

14. In a typewriter, in combination, a frame, a carriage mounted for reciprocatory movement thereon, a platen rotatably mounted thereon, line-spacing mechanism for rotating the platen, and means comprising a central platen-shaft, a hollow cylindrical shaft rotatably mounted thereon, a part of said hollow shaft being within the platen, a stop on the platen, a stop on the hollow shaft engaging said platen-stop, a helical groove on the outside of said hollow shaft, a bracket mounted on the frame, said bracket supporting a toothed wheel, which has a part that travels in said groove, and a stop on said bracket, said wheel and said stop being movable with reference to each other to engaging and to disengaging positions, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

15. In a typewriter, in combination, a frame, a carriage mounted for reciprocatory movement thereon, a platen rotatably mounted thereon, line-spacing mechanism for rotating the platen, and means comprising a central platen-shaft, a hollow cylindrical shaft rotatably mounted thereon, a part of said hollow shaft being within the platen, a stop on the platen, a stop on the hollow shaft engaging said platen-stop, a helical groove on the outside of said hollow shaft, a bracket mounted on the frame, said bracket supporting a toothed wheel, which has a part that travels in said groove, a stop on said bracket, said wheel and said stop being movable with reference to each other to engaging and to disengaging positions, and means for moving said wheel and said stop into engaging position, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

16. In a typewriter, in combination, a frame, a carriage mounted for reciprocatory movement thereon, a platen rotatably mounted thereon, line-spacing mechanism for rotating the platen, and means comprising a central platen-shaft, a hollow cylindrical shaft rotatably mounted thereon, a part of said hollow shaft being within the platen, a stop on the platen, a stop on the hollow shaft engaging said platen-stop, a helical groove on the outside of said hollow shaft, a bracket mounted on the frame, said bracket supporting a toothed wheel, which has a part that travels in said groove, a stop on said bracket, said wheel and said stop being movable with reference to each other to engaging and to disengaging positions, and a key for permitting said wheel and said stop to move into engaging position, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form.

17. In a typewriter, in combination, a frame, a carriage mounted for reciprocatory movement thereon, a platen rotatably mounted thereon, line-spacing mechanism for rotating the platen, and means comprising a central platen-shaft, a hollow cylindrical shaft rotatably mounted thereon, a part of said hollow shaft being within the platen, a stop on the platen, a stop on the hollow shaft engaging said platen-stop, a helical groove on the outside of said hollow shaft, a bracket mounted on the frame, said bracket supporting a toothed wheel, which has a part that travels in said groove, and a stop on said bracket, said wheel and said stop being movable with reference to each other to engaging and to disengaging positions, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form, and comprising a stop on said bracket which engages the platen to prevent overthrow of the platen. 20
18. In a typewriter, in combination, a frame, a carriage mounted for reciprocatory movement thereon, a platen rotatably mounted thereon, line-spacing mechanism for rotating the platen, and means comprising a central platen-shaft, a shaft mounted thereon for rotation therewith and having a helical screw, and means mounted on the frame and coacting with said screw during the carriage return to line-space the platen. 25
19. In a typewriter, in combination, a frame, a carriage mounted for reciprocatory movement thereon, a platen rotatably mounted thereon, line-spacing mechanism for rotating the platen, and means comprising a central platen-shaft, a shaft mounted thereon for rotation therewith and having a helical screw, and means mounted on the frame which by the motion of the carriage return acts on said screw to line-space the platen. 30
20. In a typewriter, in combination, a frame, a carriage mounted for reciprocatory movement thereon, a platen rotatably mounted thereon, line-spacing mechanism for rotating the platen, and means comprising a central platen-shaft, a hollow cylindrical shaft rotatably mounted thereon, a part of said hollow shaft being within the platen, a helical groove in the hollow shaft, and a stop pivoted on the platen so that it follows said groove, automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form. 35
21. In a typewriter, in combination, a frame, a carriage mounted for reciprocatory movement thereon, a platen rotatably mounted thereon, line-spacing mechanism for rotating the platen comprising a detent-lever engaging the platen, a key, and means actuated by the key for releasing said detent-lever during the initial return movement of the carriage. 40
22. In a typewriter, in combination, a frame, a carriage mounted for reciprocatory movement thereon, a platen rotatably mounted thereon, line-spacing mechanism for rotating the platen comprising a detent-lever engaging the platen, a key, and means actuated by the key for releasing said detent-lever and for locking said line- 45
- spacing mechanism during the initial return movement of the carriage. 50
23. In a typewriter, in combination, a frame, a carriage mounted for reciprocatory movement thereon, a platen rotatably mounted thereon, line-spacing mechanism operable by the return of the carriage for rotating the platen, form-feeding means optionally operable by a return of the carriage to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form, and means actuated concomitantly with said form-feeding means to hold the line-spacing mechanism out of operative position during the form-feeding operation. 55
24. In a typewriter, in combination, a frame, a carriage mounted for reciprocatory movement thereon, a platen rotatably mounted thereon and carrying a circumferential row of detent-teeth, line-spacing mechanism operable by the return of the carriage for rotating the platen and comprising a detent engaging said detent-teeth, form-feeding means optionally operable by a return of the carriage to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form, and means actuated simultaneously with said form-feeding means to hold the line-spacing detent out of contact with the platen detent-teeth and to hold the line-spacing mechanism out of operative position during the form-feeding operation. 60
25. In a typewriter, in combination, a frame, a carriage mounted for reciprocatory movement thereon, a platen rotatably mounted thereon, line-spacing mechanism for rotating the platen, and means automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form, comprising means to prevent overthrow of the platen line-spacing rotation. 65
26. In a typewriter, in combination, a frame, a carriage mounted for reciprocatory movement thereon, a platen rotatably mounted thereon, line-spacing mechanism for rotating the platen, and means automatically operative to rotate the platen a predetermined total number of line-spaces less the number of line-spaces the platen has been already rotated by said line-spacing mechanism, whereby in a continuous work-sheet the first line of a succeeding form is automatically presented irrespective of the number of lines already imprinted on the preceding form, comprising means to prevent overthrow of the platen line-spacing rotation which comprises a stop on the platen and a stop on said rotative means. 70
27. In a typewriter, in combination, a frame, a carriage mounted for reciprocatory movement thereon, a platen rotatably mounted thereon, line-spacing mechanism for rotating the platen, and means automatically operative to rotate the 75

5 platen a predetermined total number of line-spaces less the number of line-spaces the platen has been already rotated by said line-spacing mechanism, whereby in a continuous work-sheet
 10 the first line of a succeeding form is automatically presented irrespective of the number of lines already imprinted on the preceding form, comprising means to prevent overthrow of the platen line-spacing rotation which comprises a plurality of stops on the platen and a stop on said rotative means.

15 28. In a typewriter, in combination, a frame, a carriage mounted for reciprocatory movement thereon, a platen rotatably mounted thereon, line-spacing mechanism for rotating the platen, and means automatically operative to rotate the platen a predetermined total number of line-spaces less the number of line-spaces the platen has been already rotated by said line-spacing mechanism, whereby in a continuous work-sheet
 20 the first line of a succeeding form is automatically presented irrespective of the number of lines already imprinted on the preceding form, comprising means to prevent overthrow of the platen line-spacing rotation which comprises a stop on the platen and a stop on said rotative means, and means for disengaging said stops.

25 29. In a typewriter, in combination, a frame, a carriage mounted for reciprocatory movement thereon, a platen rotatably mounted thereon, line-spacing mechanism for rotating the platen, and means automatically operative to rotate the platen a predetermined total number of line-spaces less the number of line-spaces the platen has been already rotated by said line-spacing mechanism, whereby in a continuous work-sheet
 30 the first line of a succeeding form is automatically presented irrespective of the number of lines already imprinted on the preceding form, comprising means to prevent overthrow of the platen line-spacing rotation which comprises a stop on the platen and a stop on said rotative means, and a spring for disengaging said stops.

35 30. In a typewriter, in combination, a frame, a carriage mounted for reciprocatory movement thereon, a platen rotatably mounted thereon, line-spacing mechanism for rotating the platen, power-operated carriage-return mechanism, and form-feeding means optionally operable by the power-operated carriage-return movement to rotate the platen a predetermined total number of line-spaces less the number of line-spaces the platen has been already rotated by said line-spacing mechanism, whereby in a continuous work-
 40 sheet the first line of a succeeding form is automatically presented by means of said carriage-return mechanism and irrespective of the number of lines already imprinted on the preceding form, said form-feeding means including means differentially settable for varying the predetermined total number of line-spaces, whereby forms of different size may be used.

45 31. In a typewriter, in combination, a frame, a carriage mounted for reciprocatory movement thereon, a platen rotatably mounted thereon, line-spacing mechanism for rotating the platen, power-operated carriage-return mechanism, and form-feeding means optionally operable by a portion of the power-operated carriage-return movement to rotate the platen a predetermined total number of line-spaces less the number of line-spaces the platen has been already rotated by said line-spacing mechanism, whereby in a continuous work-sheet the first line of a succeeding form is automatically presented irrespective

5 of the number of lines already imprinted on the preceding form, said form-feeding means including a device adjustable for varying the extent of said form-feeding portion of the carriage-return movement, for varying the predetermined total number of line-spaces, whereby forms of different size may be used.

10 32. In a typewriter, in combination, a frame, a carriage mounted for reciprocatory movement thereon, a platen rotatably mounted thereon, line-spacing mechanism for rotating the platen, and means automatically operative to rotate the platen a predetermined total number of line-spaces less the number of line-spaces the platen has been already rotated by said line-spacing mechanism, whereby in a continuous work-sheet
 15 the first line of a succeeding form is automatically presented irrespective of the number of lines already imprinted on the preceding form, comprising a rod slidably mounted on the frame and a stop adjustably mounted on said rod for varying the predetermined total number of line-spaces, whereby forms of different size may be used.

20 33. In a typewriter, in combination, a frame, a carriage mounted for reciprocatory movement thereon, a platen rotatably mounted thereon, line-spacing mechanism for rotating the platen, a key, power-means made operative by said key for automatically returning the carriage by power, and means made operative by said key for rotating the platen, by means of the power carriage return, a predetermined total number of line-spaces less the number of line-spaces the platen has been already rotated by said line-spacing mechanism.

25 34. In a typewriter, in combination, a frame, a carriage mounted for reciprocatory movement thereon, a platen rotatably mounted thereon, line-spacing mechanism for rotating the platen, a key, and means actuated by said key for automatically returning the carriage and for rotating the platen a predetermined total number of line-spaces less the number of line spaces the platen has been already rotated by said line-spacing mechanism.

30 35. In a typewriter, in combination, a frame, a carriage mounted for reciprocatory movement thereon, a platen rotatably mounted thereon, line-spacing mechanism for rotating the platen, a key, power-operated means made operative by said key in its depressed position for automatically returning the carriage by power and for concomitantly rotating the platen by power a predetermined total number of line-spaces less the number of line-spaces the platen has been already rotated by said line-spacing mechanism, means for holding said key depressed, and means on the carriage for automatically releasing said key from said holding means at a predetermined point in the carriage return travel.

35 36. In a typewriter, in combination, a frame, a carriage mounted for reciprocatory movement thereon, a platen rotatably mounted thereon, line-spacing mechanism for rotating the platen, a key, normally idle power-operated means conditionable by said key for automatically returning the carriage by power and for concomitantly rotating the platen by power a predetermined total number of line-spaces less the number of line-spaces the platen has been already rotated by said line-spacing mechanism, and means enabling the carriage in its return movement to determine restoration of said power-operated means to idle condition.

37. In a typewriter, in combination, a frame, a carriage mounted for reciprocatory movement thereon, a platen rotatably mounted thereon, line-spacing mechanism for rotating the platen, power-operated carriage-return mechanism, a key, normally idle form-feeding means conditionable by said key, for rotating the platen by means of the power-operated carriage-return movement a predetermined total number of line-spaces less the number of line-spaces the platen has been already rotated by said line-spacing mechanism, and means enabling the carriage in its return movement to determine restoration of said form-feeding means to idle condition.
38. In a typewriter, in combination, a frame, a carriage mounted for reciprocatory movement thereon and constantly urged to advance, a carriage-feed escapement normally controlling advance of said carriage, a platen rotatably mounted on said carriage, line-spacing mechanism for rotating the platen, carriage-return mechanism automatically becoming active at a predetermined point in the carriage-advance, form-feeding means conditionable for rotating the platen by means of the carriage-return a predetermined total number of line-spaces less the number of line-spaces the platen has been already rotated by said line-spacing mechanism, a key, a connection enabling said key to release said carriage from said escapement for resulting jump to said point where the automatic carriage-return mechanism becomes active, and a connection enabling said key to condition said form-feeding means to be actuated by the return of the carriage.
39. In a typewriter, in combination, a frame, a carriage mounted for reciprocatory movement thereon and constantly urged to advance, a carriage-feed escapement normally controlling advance of said carriage, a platen rotatably mounted on said carriage, line-spacing mechanism normally operated by the return of the carriage for rotating the platen and comprising a platen-engaging detent, carriage-return mechanism automatically becoming active at a predetermined point in the carriage-advance, normally idle form-feeding means conditionable, for operation by the return of the carriage, for rotating the platen a predetermined total number of line-spaces less the number of line-spaces the platen has been already rotated by said line-spacing mechanism, a key, and connections enabling said key to (1) release the carriage from said escapement for resulting jump to said point where the automatic carriage-return mechanism operates, (2) to condition said form-feeding means to be actuated by the return of the carriage, and (3) to retract said platen-engaging detent, and lock said line-spacing mechanism against operation during the form-feeding carriage-return.
40. In a typewriter, in combination, a frame, a carriage mounted for reciprocatory movement thereon and constantly urged to advance, a carriage-feed escapement normally controlling advance of said carriage, a platen rotatably mounted on said carriage, line-spacing mechanism normally operated by the return of the carriage for rotating the platen and comprising a platen-engaging detent, carriage-return mechanism automatically becoming active at a predetermined point in the carriage-advance, normally idle form-feeding means conditionable, for operation by the return of the carriage, for rotating the platen a predetermined total number of line-spaces less the number of line-spaces the platen has been already rotated by said line-spacing
- mechanism, a key, connections enabling said key to (1) release the carriage from said escapement for resulting jump to said point where the automatic carriage-return mechanism operates, (2) to condition said form-feeding means to be actuated by the return of the carriage, and (3) to retract said platen-engaging detent, and lock said line-spacing mechanism against operation during the form-feeding carriage-return, and means acting at a predetermined place in the return of the carriage to determine restoration of the carriage to the control of said escapement, restoration of the form-feeding means to idle condition, restoration of the platen-detent, and unlocking of the line-spacing mechanism.
41. In a typewriter, in combination, a frame, a carriage mounted for reciprocatory movement thereon and constantly urged to advance, a carriage-feed escapement normally controlling advance of said carriage, a platen rotatably mounted on said carriage, line-spacing mechanism normally operated by the return of the carriage for rotating the platen and comprising a platen-engaging detent, carriage-return mechanism automatically becoming active at a predetermined point in the carriage-advance, normally idle form-feeding means conditionable, for operation by the return of the carriage, for rotating the platen a predetermined total number of line-spaces less the number of line-spaces the platen has been already rotated by said line-spacing mechanism, a key, connections enabling said key to (1) release the carriage from said escapement for resulting jump to said point where the automatic carriage-return mechanism operates, (2) to condition said form-feeding means to be actuated by the return of the carriage, and (3) to retract said platen-engaging detent, and lock said line-spacing mechanism against operation during the form-feeding carriage-return, latching means becoming set upon operation of said key to keep said form-feeding means in active condition, to keep said platen-detent retracted, and to keep said line-spacing mechanism locked, and means enabling said carriage at a predetermined place in its return travel to trip said latching means to determine restoration of said form-feeding means to idle condition, restoration of said platen-detent, and unlocking of said line-spacing mechanism.
42. In a typewriter, in combination, a frame, a carriage mounted for reciprocatory movement thereon, a platen having a shaft and rotatably mounted thereon, an automatic carriage-return mechanism having a carriage-return rack, an adjustable margin-stop for actuating said mechanism, an adjustable margin-stop for stopping said mechanism, an escapement-feed rack, line-spacing mechanism comprising a platen-detent, a key mounted for actuation by the depression thereof, an arm and a latch for holding said key depressed, a cam mounted on the carriage for releasing said arm from the latch, means operable by the key for releasing said escapement-feed rack, a hollow shaft rotatably mounted on the platen-shaft, a helical groove on the outside of said hollow shaft, a stop on the platen-shaft and a stop on the hollow shaft interengaging each other, a toothed wheel mounted for sidewise movement parallel with the platen-shaft having a ridge which engages said helical groove, a tooth mounted on the frame proximate to said toothed wheel and engageable therewith, the return movement of the carriage tending to interengage said toothed wheel and said frame-tooth, a

spring-retained pivoted tooth having a side engagement with said toothed wheel and movable by the depression of said key out of engagement with the side of said toothed wheel but into the path of the teeth thereon, mechanism connected with the line-spacing mechanism and the platen-detent for locking and disengaging the same respectively, said carriage-cam releasing said arm from said latch after said locking and disengaging mechanism has become operative, said locking and disengaging mechanism being operative throughout the carriage-return, a spring-pressed tooth on the frame, a plurality of teeth on the platen, said spring-pressed tooth engaging one of said teeth on the platen to prevent overthrow of the automatic platen-feed, and a spring which releases said spring-pressed tooth upon the letter-space drop-back of the carriage, whereby in a continuous work-sheet the first line of a succeeding form is automatically presented irrespective of the number of lines already imprinted on the preceding form.

43. In a typewriter, in combination, a frame, a carriage mounted for reciprocatory movement thereon, a platen rotatably mounted thereon, line-spacing mechanism for rotating the platen, power-operated carriage-return mechanism and means conditionable, and operable by the power-return of the carriage when conditioned, to rotate the platen a predetermined total number of line-spaces less the number of line-spaces the platen has been already rotated by said line-spacing mechanism, whereby in a continuous work-sheet the first line of a succeeding form is automatically presented by means of the power-operated carriage-return and irrespective of the number of lines already imprinted on the preceding form, said means being normally ineffective during power-return of the carriage.

44. In a typewriter, in combination, a frame, a carriage mounted for reciprocatory movement thereon, a platen rotatably mounted thereon, line-spacing mechanism for rotating the platen, a power-operated carriage-return mechanism, a special key, and means conditioned upon the depression of the special key, and operable by the power-return of the carriage when so conditioned, to rotate the platen a predetermined total number of line-spaces less the number of line-spaces the platen has been already rotated by said line-spacing mechanism, whereby in a continuous work-sheet the first line of a succeeding form is automatically presented by means of the power-operated carriage-return and irrespective of the number of lines already printed on the preceding form.

45. In a typewriter, the combination of a frame, a carriage mounted for reciprocatory movement on said frame, a revoluble platen in said carriage, line-spacing mechanism for the platen, power-operated carriage-return mechanism, and form-feeding means for rotating the platen additionally to the line-spacing, including a rotor in said carriage, having an external screw-thread, a driving connection from said rotor to said platen, and means on said frame for engaging said screw-thread, said screw-thread-engaging means being conditionable so as to co-operate with said screw-thread to cause form-feeding rotation of said rotor and platen by a carriage-return movement effected by said carriage-return mechanism, said screw-thread-engaging means being normally ineffective to rotate said rotor and platen during a carriage-return movement.

46. In a typewriter, the combination of a frame,

a carriage mounted for reciprocatory movement on said frame, a revoluble platen in said carriage, line-spacing mechanism for the platen, power-operated carriage-return mechanism, and form-feeding means for rotating the platen additionally to the line-spacing including a rotor in said carriage, having an external screw-thread, a driving connection from said rotor to said platen, a rotatable nut constantly engaging said screw-thread, means on said frame serving to oppose lateral travel of said nut relative to said frame, wherefore said nut tends to rotate idly when said screw-threaded rotor reciprocates with said carriage relatively to said nut, and means conditionable at will to lock said nut to prevent its idle rotation during a power-driven return of said carriage, thereby to cause said rotor to be rotated and rotate said platen in form-feeding direction.

47. In a typewriter, the combination of a frame, a carriage mounted for reciprocatory movement on said frame, a revoluble platen in said carriage, line-spacing mechanism for the platen, power-operated carriage-return mechanism, and form-feeding means for rotating the platen additionally to the line-spacing including a rotor in said carriage, having an external screw-thread, a driving connection from said rotor to said platen, a rotatable nut constantly engaging said screw-thread, means on said frame serving to oppose lateral travel of said nut relative to said frame, wherefore said nut tends to rotate idly when said screw-threaded rotor reciprocates with said carriage relatively to said nut, means conditionable at will to lock said nut to prevent its idle rotation during a power-driven return of said carriage, thereby to cause said rotor to be rotated and rotate said platen in form-feeding direction, said last-mentioned means being normally ineffective, and means acting during said power-driven return of the carriage to determine restoration of said nut-locking means to normal ineffective condition following the form-feeding rotation of said platen.

48. In a typewriter, in combination, a letter-feedable and returnable carriage, a paper-feeding roller mounted in said carriage, a line-spacing mechanism for actuating said roller, a power-operated carriage-return mechanism, a key operable to effect return of said carriage by said carriage-return mechanism, and normally idle roller-driving means conditioned by said key to be actuated instead of said line-spacing mechanism and concomitantly with the power-return of the carriage to rotate said roller for effecting an extra-extensive paper-advance.

49. In a typewriter, in combination, a letter-feedable and returnable carriage, a line-spaceable paper-feeding roller mounted in said carriage, a power-operated carriage-return mechanism, a key operable to effect return of said carriage by said carriage-return mechanism, normally idle roller-driving means conditioned by said key to be driven by the power-returned carriage for effecting an extra-extensive paper-advance, and means differentially settable to utilize different portions of the carriage-return movement to drive said roller-driving means, whereby to predetermine the extent of said paper-advance.

50. The combination of a laterally reciprocable typing carriage having a line-spaceable paper-feeding roller, and roller-rotating means for effecting, at will, an extra-extensive sweep of paper-advance by means of the return-movement of the carriage, said means being normally ineffective during return of the carriage, and ar-

- 5 ranged so as to be partly conditioned for effectiveness by advancing the carriage to a particular position, said means including a key, means responsive to said key for advancing the carriage to said position, means responsive to said key to completely condition said roller-rotating means for effectiveness, and power-operated means to return the carriage from said position and effect said extra-extensive sweep of paper-advance.
- 10 51. In a typewriter, in combination, a reciprocating carriage, a revoluble platen in the carriage, a toothed detent wheel connected to said platen, a detent normally engaging said detent wheel to hold the platen in line-space position, a rack movable with the carriage and adapted for movement relatively to the carriage, a key, means actuatable by said key to cause said rack to be driven to effect rack-movement relatively to the carriage and ensuingly to return the carriage, means, conditioned by said key, to cause the returning carriage to effect an extra-extensive rotation of said platen, and means, conditioned by said key, to cause said limited rack-movement to disengage said detent from said wheel.

- 20

5 52. In a typewriter, in combination, a reciprocating carriage, a revoluble platen in the carriage, a toothed detent wheel connected to said platen, a detent normally engaging said detent wheel to hold the platen in line space position, a rack movable relatively to and with the carriage, a key, means actuatable by said key to cause said rack to be driven to move relatively to said carriage and ensuingly to return said carriage, line spacing mechanism for said platen normally 10 operable by said rack in a latter stage of its movement relatively to the carriage, said stage being preceded by a normally idle stage of the rack movement relative to the carriage, means conditioned by said key to cause the returning carriage to effect an extra-extensive rotation of 15 said platen, means conditioned by said key to suppress the line spacing stage of the rack movement relative to the carriage, and means conditioned by said key to cause said idle stage of 20 the rack movement relatively to the carriage to render said detent and wheel ineffective.

HENRY L. PITMAN.
